UNITED STATES PATENT OFFICE

95,848

DESIGN FOR A SKI BOOT

Josef Lanz, Salzburg, Austria, assignor to The
Stetson Shoe Company, Inc., South Weymouth,
Mass., a corporation of Massachusetts

Application March 16, 1935, Serial No. 55,893

Term of patent 7 years

To all whom it may concern:

Be it known that I, Josef Lanz, a citizen of Austria, and resident of Salzburg, in the Province of Salzburg and State of Austria, have invented a new, original, and ornamental Design for a Ski Boot, of which the following is a specification, reference being had to the accompanying drawing, forming part thereof, in which

The figure is a side perspective view of the ski boot showing my new design.

The opposite side of the shoe presents substantially the same appearance as the side shown, except that there is no buckle at said opposite side.

I claim:

The ornamental design for a ski boot as shown and described.

Dated, March 13, 1935.

JOSEF LANZ.
